UNITED STATES PATENT OFFICE

JOSEPH B. SMITH, OF HAVANA, ILLINOIS

DISPLAY DEVICE

Application filed December 7, 1927. Serial No. 238,413.

This invention relates to display devices, pertaining more particularly to a device including a series of hingedly mounted members that may be used to carry and display articles of manufacture, advertising matter, or to answer for directory purposes.

The device is adaptable for indoor use, as in displaying goods, or for out-of-door use, but as illustrated herein is particularly fitted 10 as an advertising display device as well as for a directory.

An object of the invention is to provide a series of hingedly or pivotally mounted leaves for display arranged to be separately 15 inspected but which will normally lie in close order shielded from the weather.

Another object is to provide a series of pivotally mounted leaves for the display of printed information which while normally 20 lying in close order may be separated for inspection but which will be automatically returned to their compact closed positions when released.

Still another object lies in providing an 25 outdoor display device including separately hinged leaves carrying information, all of which automatically take up and maintain a close arrangement housed from the weather and not affected by wind.

30 In the appended drawing is illustrated a preferred form of the invention which however is subject to changes of minor nature.

Figure 1 is a side elevation of the device of my invention.

35 Figure 2 is a front elevation of a portion of the same.

Figures 3 and 4 are plans of portions shown in Figure 1, much enlarged, showing two different positions thereof.

40 Figure 5 is a detail of an antifriction device employed with certain of the parts shown in Figures 3 and 4.

Figure 6 is a plan of parts illustrated in Figures 3 and 4 separated from one another 45 to show their forms individually.

The device depicted herein is particularly suited for use in the open as, for instance on street corners or at so called "filling stations" for the dissemination of information, such 50 as business addresses and the like and is ar-

ranged so that the leaves thereof normally lie close together, automatically taking that position when and as they are released by one who may have been perusing their contents.

A supporting base is designated at 1 which 55 may be suitably secured upon a foundation 2. In the top 3 of said base is a hole 4 to receive therethrough and to form a bearing for a shaft 5 whose lower end is stepped in a conically formed recess 6 of a member 7 of said base. Mounted on and paralleling the shaft 5 is an arm or pillar 8 fixed with respect to said shaft. A screw 9 is threaded through a wall of the base 1, its extremity engaging in a groove 10, for example, in said shaft 5 preventing the latter from leaving its seat in the recess 6. On an offset portion 8' of said arm 8 is a portion having a substantially plane surface inclined downwardly at an angle 60 away from said arm 8, and on the latter near its upper end in spaced relation to the surface 11 is a bracket 12 secured to said frame and having an offset shaft-portion 13.

A series of frames 14 are provided each for 65 a support 15 for receiving advertising matter, or directory matter, the several frames being mounted each on a separate plate 16, 17, 18, 19. The assembly of the frames and plates is shown in Figure 3 and 4, said frame being 70 shown in close relation and separated relation in said figures respectively. That is to say, in Figure 6 wherein all of the plates are shown separated, 16 and 19 designate respectively a top and a bottom plate while 17 and 80 18 are intermediate plates, it being observed that an arm 20 of a channel form, Figure 5, extends from each but in such positions that all said arms may lie in close relation as in Figures 2 and 4. A series of these plates with 85 their arms 20 is employed at an upper and a lower corner at one edge of the frames 14 as shown in Figure 1. Each plate of each series has a central hole 21, Figure 6, the lower series receiving through the holes a pin 22 which depends freely into a hole 23 extending through the surface 11 into the portion 8'. The holes in the upper plates receive the shaft-portion 13 of the bracket 12, said 90 pin 22 and shaft-portion 13 being in line vertically forming pivots about which the 95

100

frames 14 may swing, the latter being suitably and individually secured within the channel-like arms 20. The two outermost arms 20 of the lower series of plates, i. e., the plates 16 and 19, are each furnished with a depending antifriction member to bear upon the inclined surface 11 of the portion 8'. This may be a caster, for example, not shown, or as in Figures 3, 4 and 5 it may be a steel ball 24, Figure 5, held by but rotatable in a mounting 25 affixed to each said arm mentioned, the intermediate arms not necessarily requiring this structure.

Affixed to the upper end of the arm or pillar 8 is a vane 26 which overhangs the frames 14 in the position they occupy in Figure 1, their normal position or position of rest, while beneath and suspended from the vane is a plate forming a housing, curved downwardly in two directions, Figure 2, to overhang the frames for shedding water.

Inspection of any matter of information upon the inner surfaces of the supports 15 since necessitating the separation of the frames 14 results in forcing one or both of the anti-friction members 24 up the inclined surface 11 and this naturally raises the entire series of frames, provided of course, that the arm 20 carrying the ball 24 is part of the lowermost plate 19 upon which all of the other plates rest. The lower series of plates as they arise lift the pin 22 within the hole 23, while the upper series slide upwardly upon the shaft-portion 13. The release of the frames, which with the supports 15 constitute "leaves", results in their return to the lowermost surface-portion of the surface 11 due to the weight of the entire series of frames on the ball 24 of the lowermost plate 19 carrying an outermost frame. The opposite outermost frame by its own weight will likewise be caused to close upon the intermediate ones, it being clear that the said intermediate frame will be closed together by both such outer ones.

The vane 26 since secured to the arm 8 and since paralleling the leaves in the normal positions of the latter and turning in the direction toward which the wind is blowing will always hold the leaves at their free edges away from such wind, the arm or pillar 8 swinging with its shaft 5 with respect to the base 1.

When used in stores and like places the vane and the overhanging plate 27 will not be required, obviously.

I claim:

1. A device of the nature described including in its construction a supporting base, an arm uprising therefrom mounted on a vertical axis including a vane, a display carrying member pivotally mounted on the arm on a vertical axis adapted for movement with respect to the arm, and coacting parts on the arm and member adapted to station the latter normally in a given position on said arm.

2. A device of the nature described including in its construction a supporting base, an arm arising therefrom pivoted on a vertical axis, a display carrying member pivotally mounted thereon movable about a vertical axis, said arm and said member being free to swing independently on said base and each having a part coacting to automatically station said member at a given position of rest.

3. A device of the nature described including in its construction a support, a plurality of display carrying members hingedly mounted thereon movable about a vertical axis, a part on the support and a part on each of the members coacting to close said members together and to normally station them in a closely lying group in a given position of rest.

4. A device of the nature described including in its construction a support, a plurality of display carrying members pivotally mounted thereon movable about a vertical axis common to all of them, a part on the support and a part on each of the members coacting to carry said members together in close formation and to station them in a given position of rest.

5. A device of the nature described including in its construction a support, a plurality of independently movable hingedly related display carrying members mounted to swing on said support on a vertical axis and adapted to have vertical movement relative to said support, there being a downwardly inclined surface on the support, and means on two of the members each resting upon and adapted to travel over said surface, the weight of the members causing them through said means to automatically seek the lowermost portion of said surface in their swinging and vertical movement.

6. A device of the nature described including in its construction a supporting base, an arm journaled on the base free to turn on a vertical axis, a member for carrying display matter supported on the arm adapted to swing on a vertical axis with respect thereto and coacting parts on the arm and member adapted to normally position the latter in a given position.

7. A device of the nature described including in its construction a supporting base, an arm mounted on the base swingable about a vertical axis, a vane secured on the arm extending laterally therefrom and lying in a vertical plane, a display carrying member mounted on the arm swingable upon a vertical axis, and means for automatically maintaining the member normally parallel to said vane.

8. A device of the nature described including in its construction a supporting base, an upstanding arm mounted to rotate on the base on a vertical axis, a vane secured on the arm extending laterally therefrom and lying in

a vertical plane, a plurality of display carrying members mounted on the arm on a vertical axis, said arm having a surface downwardly inclined from the line of the mounting of the members, and means on two of the members spaced from the axial line of said mounting adapted to support the weight of said members on said surface, said members adapted to travel up the inclined surface 5 when the members are manually swung lifting the latter, and said members adapted due to their weight to travel down said surface closing together at the lowest position on that surface paralleling the vane.

10 9. A device of the nature described including in its construction a series of display carrying members adapted to lie side by side in close order, each having an extension one overlying the other, a pivot member extending through all of said extensions upon which the latter are free to move axially, a support for the pivot, said support having a portion including a substantially flat surface downwardly inclined from said pivot, and a part 20 carried by certain of the members adapted to rest upon that surface, all of said members jointly seeking the lowest position thereon.

25 10. A device of the nature described including in its construction a supporting base, an upstanding arm mounted to rotate on said base on a vertical axis and having a surface inclined at an angle downward, a laterally extending vane affixed to the arm, the plane thereof paralleling a line drawn through the highest and lowest points on said surface, a display carrying member pivoted at one edge 30 on a vertical axis on the arm, and an anti-friction member carried by the member and bearing upon said inclined surface.

35 40 In testimony whereof I affix my signature.
JOSEPH B. SMITH.
